UNITED STATES PATENT OFFICE.

FREDERIC K. PLYMPTON, OF WELLESLEY, MASSACHUSETTS, ASSIGNOR TO PLYMPTON MANUFACTURING COMPANY, OF BOSTON, MASSACHUSETTS, A CORPORATION OF MASSACHUSETTS.

TAG.

1,159,329.

Specification of Letters Patent.

Patented Nov. 2, 1915.

Application filed December 19, 1911. Serial No. 666,684.

To all whom it may concern:

Be it known that I, FREDERIC K. PLYMPTON, a citizen of the United States, residing at Wellesley, in the county of Norfolk, State 5 of Massachusetts, have invented a certain new and useful Improvement in Tags, of which the following is a specification, reference being had therein to the accompanying drawings.

10 The invention provides an improved tag applicable either as a shipping-tag, or as a baggage-tag, price-tag, or for general purposes as a label.

It has relation to the means of securing a 15 string or wire to a tag or label for use in attaching the latter to a package or the like, and more particularly to means of reinforcing the tag or label to prevent the same from being torn away from the string or wire too 20 easily, and of obviating injury or weakening of the string or wire.

Tags of the kinds at present most generally in use have a hole punched near one 25 end of the same, and the attaching string or wire is passed through such hole. The tag is reinforced around the hole by washers of paper-material applied to both surfaces, and in some cases, in addition, the 30 hole is bushed with a metal eyelet.

35 The invention dispenses with the hole in the tag, and obviates the threading of an attaching string or wire therethrough, as well as with the special operation by which the string or wire is secured so as to prevent it from escaping from the hole. It dispenses, also, with the washers and eyelet heretofore applied in conjunction with the hole to prevent the string or wire from tearing out of the hole.

40 The invention, further, enables the tag to be made complete, with string or wire fastened thereto in a manner precluding accidental detachment from the tag, by simple and rapidly-performed operations, and by 45 automatic machinery having a high productive capacity.

The invention consists in a tag in which an attaching string or wire is secured against one edge thereof by means of a U-shaped strip of sheet-metal bent around the string or wire and the end-portion of the tag, with its legs lying at the surfaces of the tag, and in which a reinforcing strip or strips intervenes between the legs and the 55 tag, with burs driven from said legs into the

reinforcing material and the tag and upset therein. An important function of the reinforcing material is to provide increased substance to receive the burs and give the latter a more effective hold. Preferably the 60 reinforcing material embraces the string or wire and protects the same from being cut by the edges of the sheet-metal strip.

Embodiments of the invention are shown in the drawings, in which latter,—

Figure 1 shows one face of a tag having the main features of the invention applied thereto. Fig. 2 shows the other face of such tag. Fig. 3 is a view in longitudinal section on lines 3, 3, of Figs. 1 and 2. Fig. 4 shows 70 one face of a tag made in accordance with the invention, and in which the reinforce serves as a protection for the attaching string or wire. Fig. 5 shows the other face of the tag of Fig. 4. Fig. 6 is a view in longitudinal section on lines 6, 6, of Figs. 4 and 5.

Referring first to Figs. 1, 2 and 3, the sheet of material constituting the tag itself is marked 1, and 2 is an attaching string, 80 only a portion of the length of the latter being shown.

At 3 is a strip of reinforcing material which is bent around one end of the tag, with its bend fitting against the edge of such 85 end and its legs lying upon the surfaces of the tag. Preferably, though not necessarily in all cases, the reinforcing strip is cemented to the said surfaces, greater strength and resisting capacity being thereby secured. The 90 U-shaped sheet-metal strip is marked 4. It is bent around the string and the end of the tag, with its legs lying outside the reinforcing strip. The bend of the sheet-metal strip presses firmly against the exterior of the reinforcing strip, and clamps the string securely so as to prevent accidental withdrawal of the string. Burs 4^a, 4^a, struck from the legs of the sheet-metal strip into the reinforcing material and the thickness 100 of the tag, and upset therein, secure the sheet-metal strip in place upon the end of the tag. These burs being located at different points in the length of the legs of the bent strip fasten the said legs closely to the opposite sides of the tag and prevent them from springing away therefrom.

Consequently, the cord or wire is securely clasped transversely between the legs, thus further securing it from displacement.

In the preferred embodiment of the invention which is represented in Figs. 4, 5 and 6, the reinforcing strip 3 intervenes between the string and the sheet-metal strip, and its width is greater than that of the strip. The side-portions of the reinforcing strip project beyond both edges of the sheet-metal strip, as shown, so that when strain is applied tending to pull the tag away from the string the said projecting portions bend upward at such edges and prevent the string from contacting with the edges and thereby becoming chafed and cut.

What is claimed as the invention is:

15. 1. The combination with the tag or label proper, and the attaching string, of the U-shaped sheet-metal strip or piece clasping the string and a marginal portion of the tag or label proper within its bend or bight, and
20. a reinforcing strip also clasped between such strip or piece and the tag, the said strip or piece having its respective limbs formed each with one or more burs intermediate the said bend or bight and the ends of the limb which are set in the material of the tag or
- 25.

label proper and the reinforcing material from the opposite faces of the latter and clenched.

2. The combination with the tag or label proper, and the attaching string, of the U-shaped piece or strip clasping a marginal portion of the tag or label proper and an intermediate portion of the length of the string and clamping the string within its bend or bight, with its respective limbs 35 permanently secured at intermediate points in their lengths to the opposite sides of the tag or label proper, and reinforcing material wider than the said U-shaped piece or strip and intervening between the string and such piece or strip and clamped between said legs and the tag, the said reinforcing material protecting the string from the edges of the U-shaped piece or strip.

In testimony whereof I affix my signature 45 in presence of two witnesses.

FREDERIC K. PLYMPTON.
